UNITED STATES PATENT OFFICE.

BENJAMIN H. RUXTON, OF TOLEDO, OHIO, ASSIGNOR TO THE TOLEDO MOULDING COMPANY, OF SAME PLACE.

DESIGN FOR A CURTAIN-POLE.

SPECIFICATION forming part of Design No. 22,271, dated March 7, 1893.

Application filed February 10, 1893. Serial No. 461,823. Term of patent 7 years.

To all whom it may concern:

Be it known that I, BENJAMIN H. RUXTON, of Toledo, county of Lucas, and State of Ohio, have invented a certain new and original Design for Curtain-Poles; and I do hereby declare that the following is a full, clear, and exact description of the invention, which will enable others skilled in the art to which it appertains to make and use the same, referring to each being had to the accompanying drawings, and to the figures of reference marked thereon, which form part of this specification.

My invention relates to a design for curtain poles.

15 The leading feature of my design consists in a pole having its outer surface ornamented by a plurality of scallops, the scallops being a certain distance apart around the pole, leaving alternately plain and scalloped surfaces 20 extending the entire length of the pole.

Figure 1 is a front elevation of a curtain pole, showing my design. Fig. 2 is a sec-

tional end view of the same, this view being enlarged to more clearly show the design of the same.

In the drawings, 1 designates the pole, 2 the longitudinal scallops, and 3 the plain surfaces. The scallops are of uniform size throughout their length, and extend the entire length of the pole. The pole being of a uniform diameter, and when thus ornamented is used as a curtain pole, and presents a pleasing and unique appearance.

What I claim is--

The design for a curtain pole, substantially as shown and described.

In testimony that I claim the foregoing as my own I hereby affix my signature in presence of two witnesses.

BENJAMIN H. RUXTON.
